IRONER PAD

John A. Castricone, Peoria, Ill., assignor to
 Altorfer Bros. Company, Peoria, Ill., a corpora-
 tion of Illinois

Application April 26, 1939, Serial No. 270,138

1 Claim. (Cl. 38—65)

This invention relates to padding for ironer bucks or rolls and will be described as applied to the roll of a domestic roll ironer.

All machine ironing is done on a yielding or padded surface because the mechanics of ironing require resilience in the cloth-supporting surface to compensate for irregularities in the material ironed and any lack of accuracy of contact between the ironer shoe and buck. Further, such padding must have the ability to absorb the moisture from the material being ironed because ironing is the process of removing moisture from cloth as it is smoothed or pressed. In a roll ironer the moisture is removed as the material passes by the ironer shoe firmly and resiliently supported between the shoe and the padding. It will be appreciated that this requires a very short space of time and that the moisture removed from the cloth must be largely driven into the padding. It is estimated that 80% of the moisture removed in the ironing process must be absorbed into the padding during the short space of time the material passes by the shoe. The same conditions apply in press ironing where the moisture is driven into the buck as the shoe holds the cloth in contact with the buck.

Ironer padding has largely been made of fabrics such as thick cotton warp materials or felts of wool or mixed materials. Such pads readily become water-soaked and thus lose their ability to absorb moisture. Because of their lack of ability to evaporate or otherwise dispose of the absorbed moisture, such fabric paddings also lose their resiliency after a short period of use and have a tendency to become hard, which destroys their ironing efficiency. Thus fabric pads lose their effectiveness and the ironer is blamed for deficiencies in ironing which are wholly the result of this loss in padding efficiency.

Various expedients have been practiced to overcome this fault. Pads have been mounted on springs to retain their resiliency. In commercial laundries pads are removed at frequent intervals and fluffed up and rested while replacement pads are in use. Metal fiber padding has become popular in commercial laundries.

However, none of these expedients are entirely feasible in domestic ironers because of economic considerations and the housewife's lack of the required skill to remove and properly replace the pads. Also domestic ironers, used as they are for only four or five hours one day a week and then stored idle, subjects the padding to particularly hard conditions. The wet, damp pad is usually closed within a cabinet top where there is no cir-

culation of air and thus it remains damp over a long period of time.

The particular object of this invention is to provide a low-cost ironer pad that resists water soaking, that is quickly dried out in normal service and that retains its resiliency for a long period of use.

Other objects and benefits will be disclosed in the following descriptions and drawing in which:

5 Fig. 1 is a front elevation view of a domestic ironer roll mounted on an ironer head with the ironer shoe in position;

10 Fig. 2 is an enlarged broken sectional view of the ironer roll, padding, covers and shoe as it 15 would appear on the section lines 2—2 of Fig. 1; and

Fig. 3 is a small top isometric view showing the pad as made in its flat development.

Now referring to Fig. 1, I show a conventional 20 ironer roll 10 complete with padding and cover which is mounted on an ironer head 12 and has a conventional ironer shoe 11 in working relationship to the roll. This is a conventional structure which will be well understood and need not 25 be explained in further detail.

Now referring to Fig. 2, I show in section the tubular roll 13 with padding mounted thereon and with the ironer shoe 19 in ironing contact with the padding. The shoe 19 has a conventional heating element 20 clamped against its inner surface to apply heat and has a shoe cover 21 enveloping and enclosing the heating elements or other heating means.

30 35 My ironer pad is actually a quilted pad, the stuffing material 16 being completely enclosed within a fabric 14 and quilted by stitching 17, as shown. Attached to the quilted section is a plain fabric section 15 as clearly shown in Fig. 3. I 40 make an accurate development of the roll padding which can be wrapped around the roll 13 with the edges abutting at 19 and being compressed and held in position by the flap 15 which is wrapped around the quilted section and securely 45 held in place by stitches 18 lengthwise of the pad.

I employ glass wool stuffing 16 and select for 50 my purpose a rather coarse, tough grade of glass wool which is both resilient and water-proof. As the quilted section is stuffed in its flap development it is approximately three times as thick as it becomes when applied on the roll 13. As an example, for domestic roll ironers I employ a glass wool quilt of about 1½" thickness 55 but when applied on the roll 13 and compressed

by the flap 15 this thickness is compressed to about $\frac{1}{2}$ " of thickness.

The surface of the roll is then finished by applying in a conventional manner about two wraps of canton flannel covering 22 and a conventional cover 23. This method of finishing a roll as aforesaid is conventional and need not be described in further detail.

The use of glass wool for padding as above described, is made possible by my quilting and compression method. It will be appreciated that by this method I confine the glass wool stuffing within the quilted cover 14 and by the stitching 17 so that it cannot be moved to any extent when applied to the roll. This, in conjunction with my compressing the pad by the flap 15 as described, gives me a firm resilient waterproof padding that retains its life for a long period of time. The glass wool is non-absorbent but will freely permit steam and moisture to be driven into the openings between the fibers and as the glass wool fibers readily absorb heat, they attain and maintain sufficient temperatures to rapidly

drive out such moisture. Moreover, the padding being extremely porous, is readily aerated, which greatly assists the drying action when the machine is stored. To assist such drying action I 5 provide a series of openings 24 in the shell. Also, the glass wool 16 being neither animal nor vegetable matter, it does not become mouldy.

Having thus described my invention, I claim:

In an ironer buck pad, a completely enclosed 10 cloth fabric section, an inorganic matted fiber stuffing enclosed within said section, quilt stitching throughout the enclosed section, said enclosed cloth section and stitching co-acting to compress the fiber stuffing to a fraction of its 15 loose volume and to retain the fibers within the enclosed quilted section with developed dimensions to fit the buck, and a fabric flap attached to the quilted section, said flap being of sufficient length to envelop the pad on the buck, 20 whereby the pad may be first compressed in firm resilient quilted form, applied to fit the buck and retained in compressed relation on the buck.

JOHN A. CASTRICONE.
